UNITED STATES PATENT OFFICE.

RALPH R. ADAMS, OF YONKERS, NEW YORK

RAZOR.

Application filed November 11, 1916, Serial No. 130,722. Renewed May 14, 1923.

To all whom it may concern:

Be it known that I, RALPH R. ADAMS, a citizen of the United States, and a resident of Yonkers, county of Westchester, State of New York, have invented new and useful Improvements in Razors, of which the following is a specification.

This invention relates to improvements in safety razors of the so-called "wafer" blade type which have in recent years come so generally into use.

Such razors comprise essentially a blade of thin flexible sheet steel and a holder having a guard for protecting the edge of the blade and some means for clamping or otherwise securing the blade in place. It has been the observation of users of razors of this type that the blade shaves cleaner near the ends than in the middle. The reason for this is that in using such razors the guard backed by the blade is pressed against the face with an appreciable force so that the razor might be said to be pressed into the face, thereby drawing the skin at the ends of the blade and causing a greater pressure at these points.

It has been attempted to remedy this defect by curving the edge of the blade so as to have it somewhat wider in the middle than at the ends, but this construction is open to the serious disadvantage that the cost of grinding blades with curved edges is too great to allow the blades to be sold at a price such that they can be discarded when dull. The straight edge blade which is made from a continuous band can be manufactured at much cheaper cost.

The object of my invention is to provide a razor in which ordinary straight edge blades may be used, but which will shave with uniform smoothness or closeness throughout the entire length of the blade.

In the accompanying drawings I have illustrated a razor of common design modified to embody my improvements, but it will of course be understood that my improvements may be applied to the razors of other design, and that the type is selected by way of illustration only.

In said drawings,

Fig. 1 is a vertical section through the razor with the blade clamped in place;

Fig. 2 is a vertical section parallel with the shaving edge of the razor; and

Figs. 3 and 4 are detail views of different parts.

Referring to the drawings, 1 indicates the main piece or head of the razor which is threaded on the usual handle 2. At its ends the head 1 is provided with upstanding ears 3, the ends 4 of which are turned inward a short distance, as shown more particularly in Figs. 2 and 3.

The guard piece 6 is loosely supported on the upper face of the head 1 by means of notches 7 in each end which engage the upstanding portion of the ears 3. The guard is held against complete detachment by the inturned portions of the ears. On the under side of the guard piece a transverse rib 8 is provided in a position to be engaged by the end of the handle 2 where it is screwed into the head.

The ears 3 are provided at the juncture of the inturned part with the upstanding part with a lug 5 which extends toward the guard piece 6, but sufficiently spaced therefrom to allow the blade 9 to be inserted between the upper face of the guard piece and the under edge of the lug. The blade 9 is provided at each end with notches 10 of a width to receive the lugs 5 when the guard piece 6 is raised by screwing the handle through the head 1 against the rib 8. The handle is provided with a shoulder 11 at the base of its screw threaded end in a position to engage the under face of the head 1 and limit the upward movement of the guard and blade, as will be later described.

The guard 6 is preferably made of some elastic metal such as hard brass or steel, which may of course be nickel or silver plated, to prevent corrosion, and provide a suitable finish.

In using the razor the handle is unscrewed sufficiently to allow the guard piece 6 to drop against the face of the head so that the blade may be inserted under the inturned portion 4 of the ears to bring its notches in alignment with the lugs 5. The handle is then screwed in, elevating the guard and blade until the blade is clamped between the guard and the portions of the ends 4 which project beyond the lugs. When the handle is screwed in just sufficient to clamp the blade against displacement, the blade and guard will be straight. The guard, however, as stated, is formed of elastic metal and the shoulder 11 on the handle is so positioned that the handle may be screwed further into the head before the shoulder engages the under face of the head. As the

handle is screwed in the guard and blade will be bowed upwardly from the middle or away from the head, as illustrated in Fig. 2. The shoulder 11 is positioned to limit the movement of the handle to effect the maximum degree of curvature which can be safely or advantageously employed. The blade need not, however, be curved the full amount provided for, but the handle may be screwed in a greater or less degree to suit the individual requirements of the user. The elasticity of the guard piece holds the handle against looseness in its thread in all the intermediate positions of adjustment. 15 The lugs 5 hold the razor blade in proper relation to the guard and the inturned ends 4 project sufficiently over the ends of the blade to hold the blade in place when bent to the greatest curvature allowed by the shoulder 11. The ends 4 should, however, project as little over the ends of the blade as necessary to securely hold the blade thereby leaving the upper face of the blade free throughout substantially its entire 20 length so that it may be readily curved with the guard.

In shaving, the razor is pressed against the face with the exposed surface of the blade at a slight angle to the cheek, so that the middle portion of the edge first contacts with the skin and under the pressure usually applied in shaving, the entire length of the edge will be effective and instead of shaving close merely at the ends of the blade the entire edge of the blade will produce a uniform 25 cut.

Another advantage of my improved razor is that a close shave may be effected in the hollows of the face, for instance, in the cleft 30 of the lip. The convex middle portion only of the blade is used and will fit into the depression and shave clean.

When the razor is taken apart and the blade removed, it again becomes flat and 35 may be easily stropped or honed with the usual appliance for the purpose.

It will be understood that my improve-

ment may be applied to razors of other design than that shown, by modifying the blade-engaging faces of the clamping parts 40 to curve the blade on an axis transverse of its length.

It is also to be understood that my invention is not limited to the construction shown, except in so far as recited in the appended 45 claims.

I claim:

1. In a safety razor the combination of a flexible blade, a flexible guard therefor and means for holding said blade and guard in 50 shaving position with the edge of the blade and the adjacent portion of the guard appreciably curved on an axis transverse to the length of the blade and for varying the degree of curvature of said blade and guard. 55

2. In a safety razor the combination of a flexible blade and a blade holder comprising a flexible guard, and means for clamping the blade against the guard in close conformity and curving the blade and guard on an axis 70 transverse to the length of the blade.

3. In a safety razor the combination of a flexible blade and blade holder comprising members for engaging the end of the blade, a flexible guard underlying the blade, and 75 means for elevating the middle portion of the guard to thereby curve the blade and guard in close conformity on an axis transverse to the length of the blade.

4. In a safety razor the combination of a flexible blade and blade holder comprising members for engaging the end of the blade, a flexible guard underlying the blade, and means for elevating the middle portion of the guard to thereby curve the blade and guard on an axis transverse to the length of the blade, said elevating means being adjustable to different positions to vary the curvature of the blade and guard. 80 85

Signed at New York city, in the county of New York, and State of New York, this 27th day of October, 1916. 90

RALPH R. ADAMS.
